UNITED STATES PATENT OFFICE.

GEORGE E. NICKOL, OF BALTIMORE, MARYLAND, ASSIGNOR TO LYON, CONKLIN & CO., OF BALTIMORE, MARYLAND, A CORPORATION OF DELAWARE.

GAS-BURNER.

1,081,275.

Specification of Letters Patent.

Patented Dec. 9, 1913.

Application filed March 7, 1913. Serial No. 752,546.

To all whom it may concern:

Be it known that I, GEORGE E. NICKOL, a citizen of the United States, residing at Baltimore, in the State of Maryland, have 5 invented certain new and useful Improvements in Gas-Burners, of which the following is a specification.

This invention relates to an improved gas-burner of the type in which the gas-controlling valve is known as a "needle valve."

The so-called "needle valve" of gas-burners is usually a steel stem having a screw-thread that turns in and engages a 15 thread in the metal body-part of the burner; at one end the stem is provided with a head or knob which serves to turn the stem, and the other end of the stem has a cone-shaped or tapered point that opens and closes the 20 small aperture out through which escapes the gas. By turning the stem one way the tapered point is forced into and closes the said small aperture, and by turning the stem in the reverse direction the tapered point 25 recedes and opens said aperture. The frequent opening and closing of this valve by the endwise movement of the tapered point, has the effect to gradually expand and enlarge the gas aperture, until it becomes so 30 large as to unfit it for producing the purpose intended, which of course is a serious objection.

The object of the present invention is to provide an improvement in this type of 35 burner by which the same endwise movement of the valve-stem may be employed, and a similar gas-aperture, but without the objectionable result noted.

The invention is illustrated in the accompanying drawing in which,

Figure 1 is a section view of part of a burner. Fig. 2 is a view, on a larger scale than Fig. 1, of the screw cap which has the gas-escape aperture; this view looks into the 45 cap. Fig. 3 is a section view of the screw-cap.

The body-part of the burner has a small

gas-chamber, 4, the entrance to which has a screw-thread, 5, for the attachment of a pipe (not shown) that supplies the gas; the 50 body has a longitudinal bore for the valve-stem, 6, which is provided with a screw-thread, 7, and at one end has a head or knob, 8. By turning the valve-stem the screw-thread causes it to move endwise. The 55 smooth part of the stem near the head, 8, turns in packing, 9, in a stuffing box formed by a screw-collar, 10. The stem at its other end has a cone-valve, 12, that closes against a seat, 11, in the bore. Between the cone- 60 valve, 12, and the screw-thread, 7, the valve-stem, 6, is smaller than the bore, and a gas- 65 passage, 13, leads from the small chamber, 4, to that part of the bore between the valve-seat, 11, and said screw-thread. It will be 70 understood that when the cone-valve, 12, is in close contact with the seat, 11, gas communication is cut-off from the gas-chamber, 4, to the reduced passage, 14, at the end of the body and also to the escape aperture, 15. 75

The body-part end, 16, has an exterior screw-thread with which a screw-cap, 17, engages; the aperture, 15, is in the cap. This cap and the end, 16, form an enlarged chamber, 18, at the end of the passage, 14; the point 75 end of the valve never projects from the end of the passage, 14. At the inner side of the cap and surrounding the outlet or aperture, 15, is an inward projection or point, 19; this gives greater length to the outlet or 80 aperture which tends to prevent a sputtering of the escaping gas, and the point, 19, reduces the chances of any small particle of dirt, that may be in the gas, closing said aperture; the enlarged chamber serves to 85 collect the small particles.

It will be seen that the outlet or aperture, 15, in this improved structure, will not be expanded or enlarged by the action of the point-end of a needle-valve.

Having thus described my invention what I claim and desire to secure by Letters Patent is:—

In a gas burner, the combination of a

body-part having a bore provided therein with a valve-seat; a valve having a stem screw-threaded and working in said bore; and a cap taking over and covering the end 5 of said body-part and forming a chamber larger than said bore and said cap provided at its inner side with an inward projection or point, 19, and said cap having an aperture

which extends through the cap and through said inward projecting point.

10

In testimony whereof I affix my signature in presence of two witnesses.

GEORGE E. NICKOL.
